Primary Examiner — Katherine Glennon*Assistant Examiner* — Yuan Yuan(74) *Attorney, Agent, or Firm* — Tuggle Duggins P.A.; Blake P. Hurt(57) **CLAIM**

The ornamental design for a stuffed bear, as shown and described.

DESCRIPTION

FIG. 1 is a front elevational view of a stuffed bear showing my new design;

FIG. 2 is a back elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a top, front, right side perspective view thereof. The broken lines in the figures illustrate portions of the stuffed bear that form no part of the claimed design.
